LOCOMOTIVE

Otto Engler, Cassel-Wilhelmshöhe, Germany, assignor to Schmidt'sche Heissdampf-Gesellschaft m. b. H., Cassel-Wilhelmshöhe, Germany, a corporation of Germany

Application January 29, 1933, Serial No. 589,706,
and in Germany February 28, 1931

11 Claims. (Cl. 122—37)

The invention relates to locomotives having high pressure water tube boilers and low pressure smoke tube boilers, the purpose of which is to provide a mounting of the high pressure boiler drum and a connection between this drum and the low pressure boiler in an especially advantageous manner. The invention consists in mounting the front end of the high pressure drum, the rear end of which is mounted on the fire box wall, in a cylindrical shell fixed on the smoke tube boiler. In this manner, even with a comparatively short smoke tube boiler, a rigid connection between the smoke tube boiler and the high pressure boiler is obtained and the great 10 rigidity of the drum is used to increase the longitudinal rigidity of the locomotive without the necessity of setting back the high pressure drum on the end nearest the low pressure drum or providing the jacket of the smoke tube boiler with 15 a set-back into which the high pressure drum extends.

In one form of the invention the shell is fixed on the outside of the fire box tube wall of the smoke tube boiler. The high pressure steam 20 drum does not extend the full length of this shell but terminates far enough short of the tube wall to leave a space between the front wall of the high pressure boiler and the fire box tube wall of the smoke tube boiler, such space being provided 25 with an opening in its upper side to permit access thereto. In this way the front manhole of the boiler drum remains accessible, a feature which is especially important when the high pressure water tube boiler is constructed as an indirectly 30 heated boiler, so that there are present in the boiler drum heating pipes through which the heating steam flows.

In a modified form of the invention, the shell in which the high pressure drum is mounted, 35 extends through the upper part of the low pressure boiler and ends in the smoke chamber. The high pressure boiler drum can then extend nearly to the smoke chamber so that the front manhole of the drum is easily accessible through the smoke 40 chamber.

In both forms of the invention, in order to provide a further connection between the low pressure boiler and the high pressure drum and for 45 generally strengthening the construction, side sheet walls are applied which are secured to the fire box tube wall of the low pressure boiler and to the jacket of the high pressure drum and which are slidably supported on the longitudinal frame 50 of the locomotive in any well known manner.

In the drawings, two forms of the invention are shown by way of example.

Fig. 1 is a longitudinal section through one form of the invention.

Fig. 2 is a perspective view of the boiler arrangement, all parts not pertinent to the invention being omitted.

Fig. 3 is a cross section on the line III—III of Fig. 1 on an enlarged scale.

Fig. 4 is a detail cross section of the connection between the high pressure drum and the smoke tube boiler.

Fig. 5 is a longitudinal section of a modified form of the invention.

In the drawings, 1 is the drum of the high pressure boiler and 2 the low pressure smoke tube boiler. For the high pressure boiler there are provided a water tube fire box and additional heating tubes which define the heating flue leading from the fire box to the smoke tube boiler. It is unimportant for the purposes of the present invention whether the steam generation in the high pressure boiler is produced by indirect or direct heating of the water contents of the boiler drum. In the locomotive shown in the drawings, 70 the boiler drum is indirectly heated by a circulating heating medium. The construction of such a boiler is well known and need not be described. It should, however, be noted that the heating steam is conducted to the heating elements 3 in the drum 1 from intermediate headers 4 and 5 to which the externally heated tubes for the heating steam are connected.

The rear end of the high pressure drum 1 is 75 slidably mounted in a cylindrical shell 6 which is

fixed on the rear wall 8 of the fire box by means of a flanged ring 7.

On the front end of the drum 1, in the form shown in Figs. 1 to 4, a cylindrical shell 10 is fitted which is fixed by a flanged ring 12 on the fire box tube wall 13 of the smoke tube 80 boiler 2.

The boiler drum 1 extends into the shell 10 only so far that between its front wall and the tube wall 13 a free space remains which is accessible through an opening 14 in the top of the shell.

The tube wall 13 of the smoke tube boiler is stiffened on the inside by braces 16 (Figs. 3 and 4) fixed on the boiler jacket 15.

On the outside of the tube wall 13 sheet walls 18 are mounted.

These sheet walls may be stiffened by angle irons.

These sheet walls which close the sides of the heating flue leading from the fire box to the smoke tube boiler (Fig. 2), are rigidly connected at their upper edges to the jacket of the high pressure drum 1.

At their lower edges they carry slide bars 19 by which they are slidably supported 100

105

110

on the longitudinal frame 20 of the locomotive. The intermediate headers 5 are suspended from the sheet walls 18 together with the heated tubes 21 leading into them. The heated tubes can expand freely by reason of this suspension and shocks to which the frame is exposed are not transmitted directly to these tubes. In the heating flue leading to the smoke tube boiler, super-heaters 22 are arranged in the space between the tubes 21.

In the form shown in Fig. 5, the shell 24 in which the front end of the high pressure drum is mounted is not fixed on the outside of the fire box tube wall 13 of the smoke tube boiler, but extends through the steam space of the smoke tube boiler and ends in the smoke chamber 25. The corresponding openings of the fire box tube wall 13 and of the smoke chamber tube wall 26 are provided with flanged rings 27, 28 to which the tube 24 is riveted. The front end of the boiler drum 1 nearest the smoke chamber carries a flanged ring 30 which is clamped in the tube 24 or riveted or threadedly mounted in it. In this way the drum 1 is rigidly connected with the smoke tube boiler. Near the fire box tube wall 13 the drum 1 carries a ring 31 which is mounted with a little play in the shell 24. But it would also be possible to arrange at this place the rigid connection between the drum 1 and the shell 24 and to mount the front end of the drum 1 nearest the smoke chamber slidably in the shell 24. The portion of the drum 1 which lies inside the smoke tube boiler purposely is not filled with heating tubes, but serves as a collecting space in which the impurities of the feed water, which preferably is taken from the smoke tube boiler, can settle out.

While I have described the shells as being cylindrical, it is quite obvious that they are so shaped only to fit the shape of the high pressure boiler drum and that other shapes of shells to fit other shapes of boiler drums would fall within the scope of the invention. The term "shell" as used in the claims is therefore intended to cover supporting extensions of any shape which substantially surround the high pressure boiler so that it is prevented from twisting in any direction from its normal longitudinal axis.

While I have described herein some embodiments of my invention, I wish it to be understood that I do not intend to limit myself thereby except within the scope of the appended claims.

I claim:

1. In a locomotive having a longitudinal frame, a high pressure water tube boiler, a low pressure smoke tube boiler, and a fire box, the rear end of said high pressure boiler being mounted on the rear wall of said fire box, and a shell secured to one vertical wall of said smoke tube boiler, the front end of said high pressure boiler extending into said shell.

2. In a locomotive having a longitudinal frame, a high pressure water tube boiler, a low pressure smoke tube boiler, and a fire box, the rear end of said high pressure boiler being mounted on the rear wall of said fire box, and a shell secured to the outside of the fire box tube wall of the smoke tube boiler, the front end of said high pressure boiler extending into said shell but terminating short of the said fire box tube wall so as to leave a space within said shell.

3. In a locomotive having a longitudinal frame, a high pressure water tube boiler, a low pressure smoke tube boiler, and a fire box, the rear end of said high pressure boiler being mounted on the rear wall of said fire box, and a shell secured to

the outside of the fire box tube wall of the smoke tube boiler, the front end of said high pressure boiler extending into said shell but terminating short of the said fire box tube wall so as to leave a space within said shell, said shell having an opening in the upper side thereof to permit access to said space. 80

4. In a locomotive having a longitudinal frame, a high pressure water tube boiler, a low pressure smoke tube boiler, and a fire box, the rear end of said high pressure boiler being mounted on the rear wall of said fire box, and a shell secured to the outside of the fire box tube wall of the smoke tube boiler, the front end of said high pressure boiler extending into said shell but terminating short of the said fire box tube wall so as to leave a space within said shell, and means within said low pressure boiler to brace said fire box tube wall. 85

5. In a locomotive having a longitudinal frame, a high pressure water tube boiler, a low pressure smoke tube boiler, and a fire box, the rear end of said high pressure boiler being mounted on the rear wall of said fire box, a shell secured to the outside of the fire box tube wall of the smoke tube boiler, the front end of said high pressure boiler extending into said shell but terminating short of the said fire box tube wall so as to leave a space within said shell, a jacket on said high pressure boiler, and sheet walls secured to said jacket and to said fire box tube wall and slidably on the frame, said sheet walls forming a flue connecting said fire box and the tubes of said smoke tube boiler. 90

6. In a locomotive having a longitudinal frame, a low pressure smoke tube boiler mounted on the front portion of said frame, a fire box at the rear of said frame, water tubes in said fire box, a shell secured to one vertical wall of said smoke tube boiler, and a high pressure boiler having its front end extending into said shell and its rear end mounted on the rear wall of said fire box, said water tubes being connected to said high pressure boiler to generate steam therein. 110

7. In a locomotive having a longitudinal frame, a low pressure smoke tube boiler mounted on the front portion of said frame, a fire box at the rear of said frame, water tubes in said fire box, a shell secured to one vertical wall of said smoke tube boiler, a shell mounted on the rear wall of said fire box, and a high pressure boiler having its ends extending into said shells and supported thereby, said water tubes being connected to said high pressure boiler to generate steam therein. 120

8. In a locomotive having a longitudinal frame, a low pressure smoke tube boiler mounted on the front portion of said frame, a fire box at the rear of said frame, water tubes in said fire box, a shell secured to one vertical wall of said smoke tube boiler, a shell mounted on the rear wall of said fire box, and a high pressure boiler having its ends extending into said shells and supported thereby, said water tubes being connected to said high pressure boiler to generate steam therein, the rear end of said high pressure boiler being 130 slidable in said fire box wall shell. 135

9. In a locomotive having a longitudinal frame, a fire box, a high pressure water tube boiler, a low pressure smoke tube boiler in front of said high pressure boiler, and a smoke chamber in front of said high pressure boiler, the rear end of said high pressure boiler being mounted on the rear wall of said fire box, a shell mounted in and extending through said low pressure boiler and communicating with said smoke chamber, 145 150

the front end of said high pressure boiler extending into said shell.

10. In a locomotive having a longitudinal frame, a fire box, a high pressure water tube boiler, a low pressure smoke tube boiler in front of said high pressure boiler, and a smoke chamber in front of said high pressure boiler, a shell mounted on the rear wall of said fire box, a shell mounted in and extending through said low pressure boiler and communicating with said smoke chamber, the ends of said high pressure boiler extending into said shells and being supported thereby.

11. In a locomotive having a longitudinal frame, a fire box, a high pressure water tube boiler, a low pressure smoke tube boiler in front of said high pressure boiler, and a smoke chamber in front of said high pressure boiler, the rear end of said high pressure boiler being mounted on the rear wall of said fire box, a shell mounted in and extending through said low pressure boiler and communicating with said smoke chamber, the front end of said high pressure boiler extending into said shell, said high pressure boiler being secured to said shell at one point only.
